United States Patent Office.

GEORGE MOSMAN, OF CHICOPEE, MASSACHUSETTS.

Letters Patent No. 64,788, dated May 14, 1867.

IMPROVED CARPET-STRETCHER.

The Schedule referred to in these Letters Patent and making part of the same.

TO ALL WHOM IT MAY CONCERN:

Be it known that I, GEORGE MOSMAN, of Chicopee, county of Hampden, and State of Massachusetts, have invented certain new and useful improvements in Carpet-Stretchers; and to enable others skilled in the art to make and use, I will proceed to describe the same, by referring to the drawings, in which the same letters indicate like parts in each of the figures.

The nature of this improvement will be understood from the specification drawings. It consists in making the jaw or jaws, which hold the tack, and the spring or springs, which yield to release the tack, both of the same piece of metal. In the accompanying drawings—

Figures 1 and 2 are face views of this improvement.

Figure 3 is an edge view of the same.

The stretcher-plate *k*, with its teeth and the shank or handle *o*, are substantially such as are in common use, the jaw or jaws *d*, (*c* springs, *a* as in my original patent,) are formed in one and the same piece of metal, or in two halves, *d d*, the back end of which is secured to the plate *k* by a screw, rivet, or holder, as may be desirable. In the manufacture of these stretchers I propose to form the recess for holding the tack sometimes in the end of the spring jaws *d*, as shown in fig. 1, and sometimes by securing pieces of metal to the outer end of the spring-jaws *d*, as shown in fig. 2. I also propose to cast or form recess in the heel of the plate *k* for the reception of the back end of the spring-jaws *d*, and to secure said spring-jaws therein by means of a screw, rivet, &c. I also propose to cast or form pins *i*, near the front end, as shown in fig. 2, between which to allow the jaw or jaws *d* to play.

I believe I have thus sufficiently explained the nature and construction of this improvement to enable others skilled in the art to make the same therefrom.

I claim the spring-holding jaws *d d*, formed in one piece of metal, in combination with the plate *k*, substantially as and for the purpose described.

GEO. MOSMAN. [L. S.]
